CLAIM

The ornamental design for a helmet, as shown and described.

DESCRIPTION

FIG. 1 is a top front left isometric view of a helmet according to a first embodiment showing my new design;

FIG. 2 is a bottom rear right isometric view thereof;

FIG. 3 is a front view thereof;

FIG. 4 is a rear view thereof;

FIG. 5 is a right view thereof;

FIG. 6 is a left view thereof;

FIG. 7 is a top view thereof;

FIG. 8 is a bottom view thereof;

FIG. 9 is a top front left isometric view of a helmet according to a second embodiment showing my new design;

FIG. 10 is a bottom rear right isometric view thereof;

FIG. 11 is a front view thereof;

FIG. 12 is a rear view thereof;

FIG. 13 is a right view thereof;

FIG. 14 is a left view thereof;

FIG. 15 is a top view thereof; and,

FIG. 16 is a bottom view thereof.

The broken lines in FIGS. 1–16 depict portions of the helmet that form no part of the claimed design.

1 Claim, 16 Drawing Sheets
